UNITED STATES PATENT OFFICE.

OSCAR A. STEERE, OF PROVIDENCE, RHODE ISLAND.

DESIGN FOR THE ORNAMENTATION OF TAPE.

SPECIFICATION forming part of Design No. 19,658, dated February 18, 1890.

Application filed August 17, 1889. Serial No. 321,147. Term of patent 7 years.

To all whom it may concern:

Be it known that I, OSCAR A. STEERE, a citizen of the United States, residing at Providence, in the county of Providence and State of Rhode Island, have invented and produced a new and original Design for Tapes, of which the following is a specification, reference being had to the accompanying drawing, forming part thereof.

10 The drawing is a view of a piece of tape showing my design.

The nature of my design is fully represented in the accompanying drawing, to which reference is made; and it consists in a tape having two marginal lines, the two lines extending along the edges, connected by a series of broken zigzag lines extending across the width of the tape at uniform intervals. 15

I claim as my invention—

The design for a tape having the ornamentation herein shown and described. 20

OSCAR A. STEERE.
